UNITED STATES PATENT OFFICE.

IRVIN F. HARRIS, OF WAXAHACHIE, TEXAS.

ROTARY DRILL BIT.

Application filed March 25, 1924. Serial No. 701,774.

This invention has reference to a rotary collapsible drill bit, novel means being provided for expanding the bit to its operative position when it is dropped into its supporting tube.

Another object of the invention is to provide means for retracting the sections of the bit when it is desired to withdraw the bit from its tube.

10 A still further object of the invention is to provide means for locking the bit in its active position, the locking result being accomplished automatically.

With the foregoing and other objects in view which will appear as the description proceeds, the invention resides in the combination and arrangement of parts and in the details of construction hereinafter described and claimed, it being understood 20 that changes in the precise embodiment of the invention herein disclosed, may be made within the scope of what is claimed, without departing from the spirit of the invention.

Referring to the drawing:

25 Figure 1 is an elevational view of a drill constructed in accordance with the invention, the bit and support thereon being shown in dotted lines.

Figure 2 is an enlarged sectional view 30 through the device.

Figure 3 is an elevational view taken at right angles to Figure 1.

Figure 4 is a longitudinal sectional view through the upper portion of the device.

35 Figure 5 is a sectional view taken on line 5-5 of Figure 4.

Figure 6 is an end elevational view of the lower section of the device.

Figure 7 is a fragmental elevational view 40 of the lower end of the lower section.

Figure 8 is an enlarged vertical sectional view through the device showing the blades in their inactive positions.

Referring to the drawings in detail, the 45 reference character 5 designates the outer supporting tube formed with passageways 6 extending throughout the length thereof, which passageways allow fluid to pass downwardly to the bit.

50 The reference character 7 designates the inner guiding tube having enlargement 26' and which is formed with lateral oppositely disposed elongated openings 8 through which the upper ends of the bits proper 55 extend. At the lower end of the tube 7 is a reinforcing band 7'.

The drill is of the sectional type and embodies a lower section 9 formed with a reduced portion to receive the sleeve 10 formed with cut out portions defining arms 10' disposed at opposite sides thereof, the walls of the cut out portions being inclined as clearly shown by Figure 3 of the drawings. A pin 12 connects the arms 10' of the sleeve 10, and at the same time provides a support 60 for the blades 13 that are formed with inclined elongated openings 14 that accommodate the pin so that upon movement of the section 9 within the sleeve 10, the blades will be guided into or out of their active 65 positions by the contact of the pin 12 with the walls of the elongated openings.

The lower section 9 is formed with spaced arms 11' which support a pin 15 that passes through the elongated openings 16 formed 70 in the blades 13 and disposed above the opening 14 which pin contacting with the walls of the openings 16 cause the blades to be held against movement when the blades have been moved to their active positions. 75

Operating within the lower section 9 is a sliding section 17 provided with an elongated opening 14' to accommodate the pin 18 that extends through the lower section 9 so that slight movement of the section 17 longitudinally of the section 9 will be permitted. Secured to the upper end of the section 17 by means of pin 17', is a sleeve 19 which is formed with lateral cut out portions 20' through which the blades 20, which 80 act to lock the sections together, extend.

The lower end of the member 17 is provided with cam surfaces 18', designed to be moved over the upper ends of the blades 13 and cooperate with the upper inclined surfaces 13' of the blades to cause the blades or lower cutting ends thereof to be extended laterally beyond the lower end of the supporting tube 5. 85

The section 19 is hollowed and provided 90 with openings through which the locking blades 20 move, the locking blades 20 being pivotally supported in the hollow portion of the sleeve 19. The blades 20 are also pivotally connected to the section 19 by means of the pin 22'. These locking blades 20 are provided with elongated openings 21 arranged at angles so that the pin 22 which is connected to the section 23 and which extends transversely thereof and which connects the furcations of the lower end of the section 23, will cause the blades 20 to move 100 105 110 115

laterally and bite into the tubular member housing the same when the device is dropped into tube 5.

In the use of the device, the device with the blades in the position as shown by Figure 8 of the drawings, is dropped into a well, whereupon the sleeve 10 moves downwardly until it contacts with the enlargements 26, the section 9 continuing downwardly, moving the pin 15 towards the pin 12. Simultaneous with this movement, the cam surfaces 18' move over the surfaces 13' of the blades expanding the blades or moving them to positions as shown by Figure 2.

15 When it is desired to remove the drilling device, the flexible member 27 is pulled which moves the sections of the drilling device upwardly, and with the sections, moves the pins 12 and 15 which ride over the inclined walls of the elongated openings in which they are positioned, to retract the blades and permit the drill to be removed.

I claim:

1. In a device of the character described, 25 an outer tube, an inner drilling member including a lower tubular section having cut out portions adjacent to its lower end and defining fingers, a pin connecting the lower ends of the fingers, a slideable member having fingers movable in the tubular section, a pin connecting the last mentioned fingers, blades having obliquely disposed elongated openings for the reception of the first mentioned pin and having elongated openings 30 for the reception of the last mentioned pin, a movable member having cam surfaces 35 adapted to engage the blades to force the blades outwardly, and means for automatically locking the inner drilling member

against rotation with respect to the outer 40 tube.

2. In a drill, an outer tube, an inner drilling member operating in the tube and including a tubular member having fingers, 45 blades pivotally supported between the fingers, a member having fingers and operating in the tubular member, means for connecting the last mentioned fingers and blades, said fingers adapted to support the blades for pivotal movement, and means operating in 50 the tubular member for engaging the blades to move the blades outwardly.

3. In a drill, an outer tube, a tubular member having fingers, blades having elongated openings disposed at oblique angles with respect to the side edges of the blades and mounted in the outer tube, a member having fingers and operating in the second mentioned tubular member, bolts connecting the fingers and operating in the openings to pivotally connect the fingers and blades, and means operating in the tubular member and contacting with the blades for moving the blades to their active positions.

4. In a drill of the class described, an outer tubular member, an inner drilling member operating in the outer tubular member and embodying sections movable with respect to each other, blades pivotally supported by the movable sections and connected intermediate their ends and having upper inclined ends, and means engaging the upper inclined ends to move the blades to their active positions.

In testimony that I claim the foregoing as my own, I have hereto affixed my signature.

IRVIN F. HARRIS.
